TICKET PRINTING AND ISSUING MACHINE

Dudley Henry Kinnard, London, and Harold Francis Ford, Wallington, England, assignors to "T. I. M." (Ticket-Issue Machines) Limited, London, England

Application June 9, 1937, Serial No. 147,340
In Great Britain April 3, 1936

2 Claims. (Cl. 235—31)

This invention relates to ticket printing and issuing machines suitable for use on tramcars and omnibuses and of the type in which the tickets are printed and issued by a rotary printing drum carrying adjustable dies for printing variable markings such as value, fare stage and class markings.

The object of the present invention is to provide an improved machine of this kind and in particular to provide improvements which will enable a very large range of value markings to be printed and registered without making the machine unduly bulky or heavy.

According to one aspect, the invention comprises a machine of the kind referred to wherein two value setting mechanisms are provided by which two independently variable value markings can be set up, means being provided for registering the values marked at each operation of the machine.

According to another aspect of the invention the machine is provided with two adjustable marking devices controlled by external setting members through the medium of sliding members mounted to rotate with the printing drum and to slide axially relatively thereto for the purpose of setting registering mechanism by which the values marked are registered during the rotation of the drum in combination with a third setting mechanism provided to adjust a third variable marking device and comprising a slideable spindle adapted to be moved into engagement with an adjusting member on the drum for the purpose of adjusting the marking device and to be moved out of engagement therewith for the purpose of permitting rotation of the printing drum.

According to another aspect, the invention comprises a machine of the kind referred to wherein three independently operable setting mechanisms are provided for adjusting three separate variable marking devices for the purpose of enabling any combination of three variable markings to be obtained.

According to one form of the invention the machine is provided with one value setting mechanism (e. g. a pence value mechanism) adjusted by an external finger operated dial plate through the medium of a sliding setting member mounted to rotate with the drum, a second value setting mechanism (e. g. a shilling mechanism) operable by an external adjusting element through the medium of a sliding setting member mounted to rotate with the drum and a class marking setting mechanism comprising

an adjusting spindle carrying a clutch member movable axially into engagement with a clutch member on the printing drum for the purpose of adjusting the class marking die and capable of being disengaged therefrom for the purpose of permitting rotation of the drum.

The invention will be more clearly understood from the following description with reference to the accompanying drawings in which:

Figure 1 is an end elevation of the machine 10 constructed according to one form of the invention,

Figure 2 is a view of the cover plate of the machine,

Figure 3 is an end elevation of the machine 15 showing the end opposite that shown in Figure 1,

Figure 4 is a top plan view,

Figure 5 is a sectional view taken on the line 5—5 of Figure 6,

Figure 6 is a rear elevation, the cover plate 20 being removed to reveal the mechanism and certain parts being shown in section,

Figure 7 is an end view similar to that of Figure 1 but with the end frame plate removed 25 to show the mechanism,

Figure 8 is a bottom plan view with the cover plate (illustrated in Fig. 2) removed and with certain parts of the mechanism shown in section,

Figure 9 is a representation of a ticket as issued by the machine, and

Figure 10 is a cross section taken on the line 10—10 of Fig. 6.

The casing of the machine shown in the drawings comprises a bed plate 1, two end frame plates 2 and 3 projecting downwardly from the ends of the plate 1 and a removable cover plate 4. The bed plate 1 also carries a ticket strip magazine or casing 5 fixed to the upper side of the bed plate near one end thereof and having an open front fitted with a hinged cover 6. The casing is provided with lugs 1a for attachment to shoulder straps for supporting the machine upon the person of the conductor in such a way that the machine can be operated and the hinged cover 6 opened for replenishment of the ticket 35 magazine while the machine is supported on the shoulder straps.

The cover 6 is held in the closed position by means of a pair of hooked levers 7 (see especially Figs. 3 and 6) pivoted to the side walls of the 40 cover 6 and united by a bar 8 which extends across the front of the cover and is provided with a finger piece 9 by which the levers 7 can be operated simultaneously. Springs 10 acting on the levers 7 tend to hold the hooked ends of 45

the levers in engagement with lugs 11 fixed to the bed plate 1 as shown clearly in Figure 3 of the drawings, the arrangement being such that an upward pressure on the finger 9 in a direction to open the cover 6 rocks the levers 1 against the action of the springs 10 so as to release the hooked ends of the levers from the lugs 11. The hooked ends of the levers are preferably shaped so that they will ride over the lugs 11 when the cover 6 is closed and snap into the fastened position automatically.

The tickets are printed on a strip taken from a roll 12 which is inserted into the casing 5 as shown in Figure 5, so that it rests upon the bed plate 1. The roll 12 is held in place by a wire frame or arm 13 which is hinged to the casing 5 at 14 so that it can be swung forward to permit of the insertion or removal of a ticket strip roll. A leaf spring 16 fixed to the hinged cover 6 is arranged as shown in Fig. 5, so that when the cover 6 is closed the spring 16 limits the movement of the frame or arm 13 in such a way as to prevent the escape of the ticket roll from the space between the frame or arm 16 and the back of the casing 5.

The bed plate 1 is formed with an opening 17 round which is fixed a ticket strip guide plate 18 consisting of a rectangular frame formed with upstanding flanges 19 by which the ticket strip 30 is guided in its passage over the bed plate 1 to the exterior of the machine. The hinged cover carries a spring loaded pressure roller 20 which engages the upper surface of the ticket strip when the cover 6 is closed so as to press the ticket strip 35 against the guide plate 18 in the manner shown in Figure 5. The pressure roller is carried between the arms of a U-shaped frame 21 which is pivoted on a spindle 22 fixed to the side walls of the cover 6 and is controlled by a spring 23 tending 40 to rock the frame in a direction to move the roller 20 towards the opening 17, this movement being limited by a suitable stop 24. The stop 24 is so arranged that when the cover is closed the frame 21 is pushed away from the stop by the engagement of the ticket strip guide plate 18 with the roller 20 so that the ticket strip is pressed 45 firmly against the ticket strip guide plate.

The machine is provided with a printing drum indicated generally at 25 mounted to rotate about 50 a horizontal axis beneath the bed plate 1 and is provided with a printing surface which is arranged to print upon the underside of the ticket strip through the opening 17 and to feed the ticket strip forward so as to eject the printed ticket from the machine.

The printing drum is fixed to a shaft 26 which extends horizontally across the machine beneath the bed plate 1 and is supported at its end remote from the printing drum by means of a ball bearing 27 (Figures 6 and 8) carried by the frame plate 3. The end of the shaft 26 projects outside the frame plate 3 and carries a crank handle 28 by which the printing drum is rotated. The printing drum is supported at the end remote from 60 the bearing 27 by means of a bearing 29 located in a recess 30 in the frame plate 2, the printing drum being supported from this bearing through the intermediary of a hollow sleeve or casing 31 fixed to the printing drum by means of a flange 32.

The main printing surface of the drum which is indicated generally at 33 in Figure 5, comprises a number of fixed dies adapted to print the frame or border 34 (Figure 9) and other invariable parts of the ticket illustrated in Figure 9 and a number 75 of adjustable dies for printing on the ticket the

value markings, a class marking the consecutive number of the ticket, the fare stage, service number and date of issue.

The rotatable dies 35 for printing the service number and the rotatable dies 36 for printing the date of issue are adjustable directly by hand, these dies being accessible when the printing drum is in the rest position shown in the drawings through an opening in the cover plate 4 normally closed by a sliding door 37 (Figure 2) which the conductor can open for the purpose of setting the dies to print the required service number and date of issue without removing the cover 4 from the machine. In Figure 9, the service or route number is shown at 38 and the date of issue at 39. The fare stage dies are carried by a pair of rotary die holders 40 and 41 (Figure 5) which are journaled upon a common spindle within the printing drum and are adjustable to print any one of a series of numbers from 1 to 99 representing the fare stages as indicated at 42 in Figure 9. The die holder 40 prints the units digit, while the die holder 41 prints the tens digit and is coupled to the die holder 40 by suitable gearing (not shown) so as to move forward through one step at the end of each rotation of the die holder 40.

The adjustment of the fare stage dies (see Figs. 5, 6 and 8) is effected by means of an adjusting spindle 43 which is mounted coaxially with the printing drum so as to be rotatable relatively thereto and is geared to the spindle 44 (to which the die holder 40 is attached) through the medium of a pair of bevel wheels 45 and a series of toothed wheels 46 carried by the printing drum.

The fare stage adjusting spindle 43 is supported near its inner end by means of a bearing 47 carried by the printing drum and projects at its outer end through the frame plate 2. An external adjusting wheel 48 is fixed to the projecting end of the spindle 43 so that the spindle can be rotated for the purpose of adjusting the fare stage printing dies.

In order to provide an indication of the fare stage to which the fare stage printing dies are adjusted, a pair of number wheels 49 and 50 fitted with suitable carrier mechanism (not shown) are supported within the sleeve 31 by means of bearing plates 51 fixed by screws to the end of the sleeve and a suitable driving lug (not shown) fixed to the spindle and engaging a units number wheel so as to adjust the number of wheels synchronously with the adjustment of the fare stage printing dies. The relevant numbers on the wheels 49 and 50 are visible through an opening 52 in the sleeve 31, the end plate 3a being formed with a corresponding opening 53 which registers with the opening 52 when the drum is in the normal or rest position shown in the drawings.

The machine is provided with a series of pence value dies for printing the pence value on the ticket as indicated at 54 in Figure 9, these dies being carried on a rotary disc or die holder 55 which is carried by a fixed spindle 56 mounted in the printing drum and is controlled by a sliding rack 57 (see Figs. 5 and 8) which is guided in a bracket 58 fixed to the printing drum and meshes with a pinion 59 fixed to the die holder 55 and rotatable therewith on the spindle 56. The rack 57 is fixed at its end remote from the printing drum to a bracket 60 fixed to a yoke ring 61 which is mounted to slide on a square portion of the shaft 26. The yoke ring 61 is located and controlled as regards its sliding movement on the shaft 26 by means of a yoke 62 carried by the sliding rack 63 which is guided in 70

brackets 64 fixed to the bed plate 1 and which meshes with a toothed pinion 65 carried by a spindle 66 supported by the bed plate 1. The spindle 66 projects through the bed plate 1 and carries at its upper end a dial plate 67 (Figure 4) formed with a series of finger holes 68 each one of which corresponds to one of the series of pence values to which the machine can be adjusted. The dial plate 67 is normally held in the position shown by means of a spring 69 located between the spindle 66 and a boss or housing 70 fixed to the bed plate 1. The conductor can adjust the dial plate to any one of a number of positions corresponding to the different positions to which the yoke ring 61 is adjustable for printing different pence fare values by placing his finger in one of the holes 68 and rotating the plate 67 until his finger is arrested by a finger stop 71 disposed above the plate 67. The finger stop 71 is carried at one end of a two-armed lever 72 pivoted at 72a and formed with a pawl 73 which cooperates with a ratchet wheel 74 fixed to the spindle 66, the arrangement being such that the pressure of the finger on the stop 71 when the dial plate 67 is adjusted as described above causes the pawl 73 to engage one of the teeth of the ratchet wheel 74 for the purpose of holding the dial plate 67 in its adjusted position against the action of the spring 69. Indication ticket values 75 are marked on the dial plate adjacent the finger holes as shown in Figure 4. The indication against each hole corresponding to the pence value to which the machine will be adjusted by placing the finger in that hole and rotating the dial plate until the finger is arrested by the stop 71.

The machine is provided with dies for printing shillings values additional to those for printing the pence values. The shillings value printing dies are carried by a rotary disc or die holder 76 which is mounted side by side with the die holder 55 on the spindle 56 and is controlled by a sliding rack 77 similar to the rack 57 and is similarly guided in the bracket 58. The rack 77 meshes with a pinion 78 fixed to the die holder 76. The rack 77 is attached at its end remote from the printing drum to a yoke ring 79 mounted to slide on the square portion of the shaft 26. This ring 79 is located between the drum and the ring 61 and is provided with an opening to accommodate the rack 57 which passes from the drum through the yoke ring 79 to the bracket 60 on the yoke ring 61. The ring 79 is controlled as regards its sliding movements on the shaft 26 by means of a yoke 80 carried by a sliding rack 81 which is guided in the brackets 64 fixed to the bed plate 1 and meshes with a toothed pinion 82 carried by a spindle 83 supported by the bed plate 1. The spindle 83 projects through the bed plate 1 in front of the spindle 66 and beneath the dial plate 67 and carries an external lever arm 84 which can be rotated by hand for the purpose of imparting sliding movement of the yoke ring 79 and adjusting the shillings value printing dies 76. Indications of the value to which the shillings printing dies can be adjusted are marked on the bed plate 1 in the path of the end of the lever arm 84 as shown at 85 in Figure 4 so as to indicate the adjustment of the machine. In order to provide for issuing a ticket of $\frac{1}{2}$ d. value the printing wheel 76 carries in addition to a number of shillings value dies a $\frac{1}{2}$ d. value die. The marking shown at 86 on the plate 1 indicates the position to which the arm 84 must be adjusted in order to print a $\frac{1}{2}$ d. value.

The machine is provided with a number of registering counters 87a, 87b . . . 87c mounted on spindles 88 disposed parallel to the shaft 26, the counters being arranged in such a way that they can be read through openings formed in the cover 5 4 as shown in Figure 2. These spindles are attached at their ends to metal plates 89, 90, so that the spindles 88 of the counters and plates 89, 90, constitute a self-supporting skeleton frame so that the whole of the counters can be detached 10 from the machine as a unit. Access to the interior of the machine for reading the counters is unnecessary, however, as the various records are all visible through openings in the cover 4 (see Figure 2) without unsealing the machine. The 15 counter 87e which is adapted to register the total pence value, i. e., the total value printed by the pence die holder 55 after being adjusted to the required amount by operation of the wheel 67 is operated by a series of mutilated gear wheels or 20 toothed discs 91 mounted side by side on a sleeve 32 fixed to the disc 61 and adapted to slide as a whole on the shaft 26.

The counter 87e is provided with a toothed wheel 93 adapted to be driven by the teeth on the 25 discs 91 when the spindle 26 is rotated by the handle 28 for printing and issuing a ticket.

The teeth on the discs 91 are arranged in progressive order starting with one tooth on the first disc, i. e., that shown at the extreme right in Fig. 30 6 to eleven teeth or any number corresponding to the pence value markings 75 on the dial plate 67.

When the machine is adjusted to print a penny ticket the discs are moved along the shaft 26 35 through the medium of yoke 62, and rack 63, to a position wherein the disc carrying one tooth is brought in alignment with the toothed wheel 93 on the counter 87e so that a single rotation of the shaft 26 will cause the counter 87e to 40 be advanced by the amount corresponding to one penny. Further rotation of the dial plate 67 to set the machine at a higher pence value causes the discs 91 to be moved bodily to the right so that successive discs are brought into line with the toothed wheel 93. Thus each disc 91 corresponds to a particular pence value and the number of teeth on each disc is chosen to accord with the pence value to which it corresponds. It is convenient to take a 1d. as the unit 50 of value so that the counter will be advanced through one unit for every 1d. of unit of value printed.

The total value of shillings is registered on a counter which is operated by a series of mutilated gear wheels or toothed discs 94 similar to the discs 91 and which are adapted to be moved along the shaft 26 by the yoke 80 attached to the shillings adjustment rack 81. There are four toothed discs 94 corresponding to the four adjustments of the arm 84 and another toothed disc 95 is provided for recording the number of $\frac{1}{2}$ d. values on a counter (not shown). Each of these toothed discs is provided with an appropriate number of teeth so that when the arm 84 is adjusted to print a particular value the particular toothed disc through the medium of pinion 82, rack 81, and yoke 80 is brought into line with the driving wheel on the shilling counter and upon rotation of the shaft 26 the 70 amount corresponding to the number of shillings printed is registered. Similarly when the arm 84 is placed at $\frac{1}{2}$ d. the toothed disc 95 is brought into line with its corresponding counter and is registered in the same way.

The die holder 76 has a blank portion which can be brought into the printing position by moving the arm 84 to the position marked blank in Fig. 4, so as to prevent any value from being printed in the shillings and ½d. position when not required. In this position of the arm 84, all the discs 94 and 95 are moved out of line with the driving wheels of their respective counters so that the counters are unaffected by the rotation of the shaft 26. The mechanism is so arranged that when the discs 94 are in the position just described the sleeve on which they are mounted acts as a stop limiting the movement of the discs 91 towards the left as seen in Fig. 8, and preventing the finger dial returning to its normal blank position as seen in Fig. 4.

When the finger pawl 73 is released, the discs 91 are moved automatically to the left under the action of the spring 69 acting on the dial plate 67. In order to prevent inadvertent displacement of the discs 94 under the action of the spring 69, a spring loaded latch 96 is provided for holding the arm 84 in the "blank" position. When the latch 96 is fastened the dial plate 67 and the die holder 55 cannot be moved to the "blank" position. Movement of the arm 84 to the ½d. value or to any of the shilling values, however, causes the discs 94 to move to the left as seen in Fig. 8 and frees the discs 91 for movement towards the left sufficiently to bring a blank part of the variable die holder 55 into the printing position.

The corresponding movement of the discs 61 brings all the toothed discs 91 clear of the driving wheel of the counter 87a so that nothing is registered on the total pence value counter.

The class dies for printing the class indications as shown at 96 in Fig. 9 are carried by a rotary die holder 97 mounted on the printing drum 25 as shown in Figs. 5, 6 and 8. This holder is adjustable by means of an adjusting spindle 98 slidably and rotatably mounted in a framework 99 fixed to the bed plate 1 of the machine and projecting at one end through the frame plate 3, an external finger disc 100 being mounted on the projecting end of the spindle as shown.

The spindle 101 on which the die holder is mounted carries a clutch member 102 and is controlled by a spring 103 which normally urges the spindle to the right as seen in Figure 8 so as to hold the clutch member 102 in engagement with a clutch member 104 fixed to the drum 25 and adapted to lock the die holder 97 in any one of its printing positions. The adjusting spindle 98 carries a pin 105 adapted to engage any one of a ring of holes 106 formed in the framework 99 of the machine and is controlled by a spring 107 which normally urges the spindle 98 to the right as seen in Figure 8 so as to hold the pin 105 in engagement with one of the holes 106 and lock the spindle in any one of a number of angular positions corresponding to those of the spindle 101. The spindle 98 is mounted so as to be in alignment with the spindle 101 when the drum is in the normal or rest position shown in the drawings and a clutch member 108 provided on one end of the spindle 98 is adapted to engage a clutch member 109 provided on the spindle 101 so that the adjustment spindle 98 can be coupled to the spindle 101 by movement of the spindle 98 to the left as seen in Figure 8 for the purpose of adjusting the class die holder. The parts are so constructed that disengagement of the clutch mem-

bers 102 and 104 cannot occur until both the clutch members 108 and 109 are in engagement and the pin 105 is disengaged from the holes 106 in the framework 99 by moving the spindle 98 to the left.

In the machine shown in the drawings, the adjustable die holder 97 is adapted to print any one of six different class markings, e. g. "mid-day", "child's", "ordinary workmen's", "workmen's returns" and "ordinary returns".

In order to provide a registration of the total number of tickets of a particular class or group of classes, a pawl or tappet member 110 mounted to rock about a pivot 111 on the drum 25 is formed with a projection 112 which can be moved into or out of line with a driving wheel of the counter 87a mounted adjacent the drum. The tappet member 110 has a pin or projection 113 adapted to engage any one of a series of recesses in the die holder 97. A spring 111a tends to rock the member 110 to the left as seen in Figure 6 so as to withdraw the projection 112 from the operative position at the same time causing the projection 113 to enter one of the recesses in the die holder 97. The recesses in the die holder are so arranged that when the die holder is adjusted to print a class marking which is not to be registered on the counter 87a the pin enters one of the recesses so that the tappet member 110 is inoperative. When the die holder 97 is adjusted to other positions, however, the pin 113 is forced out of the hole and rides on the wall of the die holder 97 so that the tappet member is held in the operative position against the action of the spring 111a and upon rotation of the drum 25 the projection 112 engages with the driving wheel of the counter 87a to advance the counter one step for each rotation of the printing drum.

The machine shown in the drawings is provided with check counters 87c and 87d driven synchronously with the pence and shillings counters. The shillings check counter 87c is driven by the toothed discs 94 and the pence check counter 87d is driven by the toothed discs 91 in the manner previously described. These check counters serve to reveal any errors due to faults in the mechanism of the counters.

A further registering counter 87d for registering the total number of rotations of the drum is provided and this counter is actuated by a projection 114 provided on the shaft 26 which advances the counter one unit for each rotation of the handle 28. The printing of the consecutive number of the ticket indicated at 115 in Figure 9 is effected by a set of numbering wheels 116 carried by the printing drum 25 (see Figure 8) and adapted to be advanced one step every time the printing drum is rotated. The numbering wheels are actuated by a fixed cam plate 117 (see Figures 5, 6 and 8) having a circular edge engaging between the teeth of a gear wheel 118 meshing with another gear wheel 119 mounted on the spindle of the numbering wheels 116. The cam plate has a part 120 which is turned radially inwards as shown in Figure 5 so that as the drum 25 rotates the part 120 of the cam turns the wheel 118 through the space of one tooth and advances the numbering wheel one unit and brings a successive tooth into engagement with the inner edge of the cam plate 117. Some part of the edge of the cam plate 117 is always engaged between two teeth of the wheel 118, so that this wheel is positively controlled at all times and accidental displacement thereof is prevented.

The machine is fitted with an inking device 75

consisting of an inked roller 121 mounted on a frame or bracket 122 which is supported on a spindle 123 fixed to the frame of the machine and is pressed towards the printing drum by two 5 springs 124 whose movement is limited by a stop 125. The ink supply roller 126 carried by the frame 127 is pressed against the inking roller by springs 128. The ink supply roller 126 is located adjacent the door 37 in the cover plate 4 through 10 which the service number and date of issue printing wheels are adjusted, the door opening being adapted also to provide access to the inking supply roller for the purpose of replenishing it with ink.

15 The frame 21 carrying the pressure roller 20 carries a serrated knife edge 129 located close to the surface of the bed plate 1 at a point where the ticket issues from the machine so that the ticket can be torn off against this knife edge by hand. 20 The portion of the ticket strip indicated at *x* in Figure 5 extending between the pressure roller and the knife edge is printed upon by a portion of the fixed surface of the printing face 33 and when a ticket is torn off against the knife edge 25 129 the part *x* of the ticket strip remains behind and forms a part of the next ticket strip. The part *x* of the ticket therefore forms part of the next ticket issued and must consequently constitute one of the invariable parts of the ticket. In 30 the machine shown in the drawings the surface 33 prints a notice as indicated at 130 in Figure 9.

In order to prevent the drum from being rotated when either of the value die adjusting devices are incorrectly adjusted and also to prevent movement of the value die adjusting devices after the drum has been moved away from its normal or rest position, a toothed bar or comb 131 is fixed in the machine as shown in Figures 6 and 8 in such a way that the edges of the discs 94 and 91 are engaged between the teeth of the comb 131 in any one of the several positions to which the discs may be adjusted. Each of the discs 94 and 91 is provided with a recess 132 which registers with the comb 131 when the drum is in the normal or rest position so as to permit axial movement of the discs 94 and 91 for the purpose of adjusting the fare value, while the drum is in the normal or rest position.

50 In order to prevent reverse rotation of the drum the spindle 26 carries a ratchet wheel 133 which is located in the end plate 3 and is engaged by a pawl 134 which is held in position by a leaf spring 135.

55 Mounted on the outside of the frame plate 3 is a lever 136 carrying a pin 137 which projects through an opening in the end plate and is engaged by a leaf spring 138 which normally holds the lever in the position shown so that a lug 139 formed on this lever lies in the path of a pin 140 carried by the crank handle 28. The engagement of the lug 139 with the pin 140 arrests the handle 28 when the drum 25 is in the normal or rest position shown in the drawings, thereby preventing accidental rotation of the 60 crank handle beyond this position. The lever 136 has a projection 141 which is located in a position convenient to the hand of the operator and permits the lever to be moved against the action of the leaf spring 138 into a position in which the lug 139 is clear of the path of the pin 140 so that the crank handle 28 can be rotated when required.

70 In the use of the machine the conductor adjusts the fare stage by rotating the wheel 48 backwards or forwards until the numbering

wheels 49 and 50 indicate through window 144 the required fare stage. The conductor will usually adjust the fare stage marking device in this way as the vehicle enters the successive stages, but in the event of a passenger being carried 5 beyond the stage at which he boarded the vehicle before the conductor issued his ticket, the fare printing device can easily be adjusted prior to the issue of that passenger's ticket to indicate the correct stage at which the vehicle was 10 boarded by the passenger.

The conductor adjusts the spindle 98 in accordance with the class of ticket which is to be issued by pushing the spindle 98 inwards against the action of the spring 107 and rotating the 15 wheel 100 until the indicating disc 142 shows the required class marking through the window 143 and then allows the spindle 98 to return to its normal position under the influence of the spring 107. 20

If a ticket of any value from 1d. to 11d. is to be issued the arm 84 is adjusted to the blank position and the finger dial 67 is then adjusted to the value of ticket required. The conductor then releases the stop lever 136 and rotates the 25 crank handle 28 through one revolution. The consequent rotation of the printing drum prints and issues a ticket marked with the fare stage, class and value markings to which the machine is adjusted and registers the issue of this ticket 30 on the total counter 87b, the total pence counter 87e and if required further indication of the class of ticket issued on the counter 87a.

For the purpose of issuing a ticket of a value not provided for by the value setting mechanism controlled by the finger dial 67, i. e., a ticket having a value of more than 11d., the conductor adjusts the arm 84 to the required value and then the finger dial 67 to the required number of pence and operates the machine in the 40 same way, the shillings value being recorded on its respective counter.

If the conductor is required to issue a ticket of a value not specifically provided for by the dies in the machine, he can make up the required value by two operations of the printing drum, stopping after the first revolution to adjust the finger dial 67 and arm 84, and then proceeding to issue a double ticket before severing the printed portion on the knife edge 129. 50

When the ticket roll 12 is exhausted the conductor opens the cover 6 by exerting an upward pressure on the finger piece 9 and releasing the arm 7 from the lugs 11, and inserting a new ticket roll. 55

In order to give the conductor warning when the ticket roll is nearly exhausted, the ticket strip may be marked with a colored line or other indication for a sufficient distance from the end of the strip. Alternatively, the magazine cover 6 may be provided with a window through which an indicator preferably in the form of a red colored disc or plate becomes visible when the ticket roll is nearing exhaustion. This indicator may be mounted on an arm bearing against the roll or an element movable therewith and maintained in such engagement by means of a spring so that when the roll is reduced to a predetermined diameter the indicator appears beneath the window to warn the conductor that the 60 magazine will shortly require replenishing. 65

The machine described with reference to the accompanying drawings is a portable machine adapted for use on trams, motor buses and the like vehicles but the machine may be adapt- 70 75

ed without material alterations in its construction to operate at a fixed point as for issuing railway or other tickets at a booking office or other fixed station. Moreover a non-portable machine substantially similar in construction and operation to that described with reference to the accompanying drawings may be associated with an electric motor for rotating the printing drum shaft, suitable clutch mechanism being provided for the purpose of obtaining a single rotation of the printing drum shaft at every operation of a switch or other control.

We claim:

1. A ticket printing and issuing machine of the class described comprising a printing drum having two independently adjustable printing devices for printing variable value markings, registering devices for said printing devices, a shaft fixed to the printing drum, actuating devices for the registering devices, a separate external setting member for each of said printing devices, and an adjusting member coupled to each of said printing and actuating devices and to the respective setting member and mounted to slide on and rotate with said shaft, each of said adjustable value printing devices being ad-

justable to a blank position in which it prints no value marking, and said adjusting members being arranged so that the movement of either of said members resulting from adjustment of the corresponding value printing device to the blank position causes the other value printing device to be adjusted to a value printing position, thereby preventing simultaneous adjustment of both adjustable value printing devices to blank positions. 10

2. A ticket printing and issuing machine of the class described comprising a printing drum having two independently adjustable printing devices for printing variable value markings, registering devices for said printing devices and a separate external setting member for each of said printing devices, each of said adjustable value printing devices being adjustable to a blank position in which it prints no value marking, and means operative by movement of either of said setting members to adjust the corresponding value printing device to the blank position to move the other value printing device to a value printing position. 15 20
